FIREARM

Kenji Murakami, 458 Hiyoshi-cho, Kohoku-ku,
Yokohama, Japan

Filed May 11, 1970, Ser. No. 22,913

Claims priority, application Japan Feb. 14, 1970

Term of patent 14 years

Int. Cl. D22—01

U.S. Cl. D22—6

FIG. 1 is a side elevational view of a firearm showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is an enlarged fragmentary side elevational view of the portion of the barrel enclosed in broken lines in FIG. 1;

FIG. 7 is a cross-sectional view taken on line 7-7 of FIG. 6;

FIG. 8 is a cross-sectional view taken on line 8-8 of FIG. 6;

FIG. 9 is a side elevational view of a second embodiment of my design;

FIG. 10 is a front elevational view thereof;

FIG. 11 is an enlarged fragmentary side elevational view of the portion of the barrel enclosed in broken lines in FIG. 9;

FIG. 12 is a cross-sectional view taken on line 12-12 of FIG. 11;

FIG. 13 is a cross-sectional view taken on line 13-13 of FIG. 11.

I claim:

The ornamental design for a firearm, as shown and described.
